CLAIM

The ornamental design for a vacuum breaker assembly
for bidet, as shown and described.

DESCRIPTION

FIG. 1 is a rear elevational view of a vacuum breaker
assembly for bidet showing our new design;

FIG. 2 is a top plan view thereof;

FIG. 3 is a front elevational view thereof;

FIG. 4 is a left side elevational view thereof;

FIG. 5 is a bottom plan view thereof; and

FIG. 6 is a right side elevational view thereof.
